[57] CLAIM

The ornamental design for a bicycle, as shown and described.

DESCRIPTION

FIG. 1 is a perspective view of the bicycle of our new design;

FIG. 2 is a side view of the bicycle of our new design, as viewed from the right side of FIG. 7;

FIG. 3 is a side view of the bicycle of our new design, as viewed from the left side of FIG. 7;

FIG. 4 is a top view of the bicycle of our new design;

FIG. 5 is a bottom view of the bicycle of our new design;

FIG. 6 is a rear view of the bicycle of our new design; and,

FIG. 7 is a front view of the bicycle of our new design.

A characteristic feature of the design resides in the large size

of the wheels of the bicycle relative to the size of the frame.
